UNITED STATES PATENT OFFICE.

JOSEPH W. DORON, OF HAMILTON, OHIO, ASSIGNOR OF ONE-HALF TO SHULER W. DORON, OF HAMILTON, OHIO.

VARIOMETER.

1,408,992.

Specification of Letters Patent.

Patented Mar. 7, 1922.

Application filed February 14, 1921. Serial No. 444,917.

To all whom it may concern:

Be it known that I, JOSEPH W. DORON, a citizen of the United States, and resident of Hamilton, in the county of Butler and State 5 of Ohio, have invented a certain new and useful Improvement in Variometers, of which the following is a full, clear, concise, and exact description, reference being had to the accompanying drawings, forming a part of 10 this specification.

My invention relates to that type of devices which are known as variometers and which are employed for the purpose of varying the inductance in wireless telephone and 15 telegraph circuits. The invention contemplates the provision of a device of this type that is of sturdy construction, which may be economically manufactured and which is more efficient than similar devices heretofore 20 produced. The device hereinafter described, and subsequently claimed, is particularly characterized by the extremely small air gap between the stationary and movable coils and by the fact that only an extremely small 25 portion of each coil lies in contact with the material of the framework supporting it.

Other advantages of the variometer of my invention will appear as the following detailed description progresses.

30 In the accompanying drawing wherein I have illustrated one embodiment of my invention,

Figure 1 is a side elevational view of the variometer.

35 Figure 2 is a top plan view thereof.

Figure 3 is a vertical sectional view taken on the line 3—3 of Figure 2, and

Figure 4 is a horizontal sectional view taken on line 4—4 of Figure 1.

40 Similar characters of reference refer to similar parts throughout the several views.

The device comprises an outer stationary coil support and an inner movable coil support. The outer support comprises the upper

45 and lower rings indicated at 10 and 11, respectively, each of which is provided with a plurality of peripheral ears 12—12. If desired, a pair of the ears of each ring may be conformed to provide brackets wherewith to

50 mount the variometer on a panel board or other suitable support as indicated in Figure 2. Sleeves 12^a—12^a are interposed between the ears of the upper and lower rings and bolts 12^b—12^b extend through said sleeves

and said ears to fasten the upper and lower 55 rings together. It will be understood that the herein illustrated means for supporting the variometer is purely representative and may, of course, be varied within wide limits.

Formed integral with or otherwise attached to each of the rings 10 and 11, is a bridge 13 which is apertured at its central point to receive one of the bearings 14—14 for the shaft 15.

The inner coil support is in the form of a 65 spool which comprises the discs 16 and 17 which are spaced from each other by sleeve 18 and are keyed or otherwise fixed upon shaft 15.

Rings 10 and 11, bridges 13, discs 16 and 70 17 and sleeve 18 are conveniently and preferably formed of non-conducting material; the other parts of the device may be formed of metal or other suitable material.

It will be noted that the discs 16 and 17 75 of the inner coil support are beveled at 19, the annular beveled surfaces thus provided being complementary to but spaced slightly from the annular beveled surfaces 20 of the rings 10 and 11. The distance between 80 each beveled surface 19 and its opposing beveled surface 20 is preferably just slightly greater than the diameter of the wire of which the several turns of the inner coil are formed. It will be noted that the upper 85 ring 10 of the outer support is provided with four upwardly projecting peripheral beads 21 and that the lower ring 11 is provided with corresponding similarly positioned downwardly projecting beads which 90 have been designated by the same reference numerals.

The outer coil consists of two sections A and B, said outer coil sections lying on opposite sides of the axis of shaft 15 and upon 95 opposite sides of the bridges 13—13. Although supported solely by the rings 10 and 11, it will be noted that the several turns of the outer coil engage the material of said rings only at their peripheries and 100 at the beads 21—21. The inner coil comprises the sections C and D which, like the corresponding sections of the outer coil, are disposed on opposite sides of the axis of shaft 15. The several turns of the inner 105 coil are carried solely by the discs 16 and 17 but it will be noted that the several turns of the inner coil contact with said discs only

at the beveled surfaces 19 and at the extremely narrow peripheral surfaces of said discs.

So far as my present invention is concerned, the inner and outer coils may be connected inside of the variometer or may be provided with separate terminals by means of which the proper electrical connections can be made. In the drawings I have indicated the usual series circuit relation between the inner and outer coils. Corresponding ends of the inner coil sections C and D are electrically connected together and the other ends of said inner coil sections are led to corresponding ends of the outer coil sections A and B. The other ends of the outer coil sections may be led to the upper ends of two of the bolts which secure the outer coil support together, said bolts and their co-operating nuts serving as terminals wherewith proper circuit connections may be made with the variometer. The wires which afford electrical connection between the inner and outer coil sections are conveniently turned once or more around the shaft, as is clearly indicated in Figure 3, this being an expedient often used in other variometer constructions.

The shaft 15 is conveniently provided with an operating knob 22 and with a pointer 24 which moves over a suitable scale 23. If desired, the dial may be provided with stops 25 which, by their co-operation with the pointer, limit the range of movement of the inner coils to an arc of 180°, this range being all that is necessary in order that the relation of the coils may be changed from turns in parallel to turns at right angles and then to the opposite position with turns in parallel.

It will be understood that I do not, in any way, limit myself to the particular arrangement and construction of parts herein shown and described, but wish to secure to myself, all equivalent constructions coming within the terms or spirit of the appended claims.

What I claim is new and desire to secure by Letters Patent of the United States, is:—

1. In a variometer, an outer support comprising a pair of spaced, relatively fixed and concentrically disposed rings, an inner coil support comprising a pair of spaced and relatively fixed circular members, each of which lies immediately adjacent one of the rings of the outer support, and concentric therewith, a coil carried by the outer support and having its several turns passing across each ring and between the rings, a coil carried by the inner support and having each of its turns passing across each circular member and between said circular members, and means for rotating one of said supports with respect to the other.

2. In a variometer, an outer support com-

prising a pair of spaced, relatively fixed, and concentrically disposed rings, an inner coil support comprising a pair of spaced and relatively fixed circular members, each of which lies immediately adjacent one of the rings of the outer support, and concentric therewith, a coil carried by the outer support and having its several turns passing across each ring and between the rings, a coil carried by the inner support and having each of its turns passing across each circular member and between said circular members, and means for rotating one of said supports with respect to the other, each of the circular members of the inner support being provided with an annular beveled coil engaging surface which is complementary to and spaced slightly from a corresponding surface on the adjacent ring of the outer support.

3. In a variometer, an outer support comprising a pair of spaced, relatively fixed and concentrically disposed rings, an inner coil support comprising a pair of spaced and relatively fixed circular members, each of which lies immediately adjacent one of the rings of the outer support, and concentric therewith, a coil carried by the outer support and having its several turns passing across each ring and between the rings, a coil carried by the inner support and having each of its turns passing across each circular member and between said circular members, and means for rotating one of said supports with respect to the other, each of the rings of the outer support being provided with beads which are the only portions of the upper and lower surfaces of the rings which engage the several turns of the outer coil.

4. In a variometer, an outer support comprising a pair of spaced relatively fixed and concentrically disposed rings, an inner coil support comprising a pair of spaced and relatively fixed circular members, each of which lies immediately adjacent one of the rings of the outer support, and concentric therewith, a coil carried by the outer support and having its several turns passing across each ring and between the rings, a coil carried by the inner support and having each of its turns passing across each circular member and between said circular members, and means for rotating one of said supports with respect to the other, each of the circular members of the inner support being provided with an annular beveled coil engaging surface which is complementary to and spaced slightly from a corresponding surface on the adjacent ring of the outer support, each of the rings of the outer support being provided with beads which are the only points of the upper and lower surfaces of the rings to engage the several turns of the outer coil.

5. A variometer, comprising a stationary outer support comprising a pair of spaced

- and concentrically disposed rings, an inner support in the form of a spool disposed with its axis concentric with the centers of said rings and with each of the spool heads lying immediately adjacent one of the rings, an outer coil having its several turns extending across and between said rings, and an inner coil having its several turns extending across and between the heads of said spool.
- 5 10 6. A variometer comprising an outer support comprising a pair of spaced and concentrically disposed rings, bridges carried by said rings and extending across their centers, a shaft journaled in said bridges, a pair of circular members carried by said shaft, each 15 circular member lying immediately adjacent one of said rings, an outer coil having its several turns extending across and between said rings, and an inner coil having its several turns extending across and between 20 said circular members.
- In witness whereof, I hereunto subscribe my name this 8th day of Feb., 1921.
